TRAVELING CRANE

John E. Minty, Muskegon, Mich., assignor, by
mesne assignments, to Manning, Maxwell &
Moore, Inc., a corporation of New Jersey

Application January 19, 1940, Serial No. 314,610

15 Claims. (Cl. 212—4)

The invention relates to improvements in traveling cranes and more particularly to cranes for use in raising, lowering and traversing such movable members as, for example, the heavy fire brick covers for high temperature furnaces or soaking pits.

As is well known, soaking pits are ordinarily arranged in side-by-side relation in one or more rows with their top covers correspondingly aligned. Cranes of the general class here in question are adapted to be positioned above the covers for raising, lowering and traversing the same, as billets or ingots are moved into and out of the pits.

One general object of the present invention is to provide such a crane which is of a character that it may be readily manipulated to raise a selected one or more of the covers or similar members in a group, all with a maximum of flexibility in the selection of the member to be raised and minimum wastage of time in operation by reason of the selection step.

More specifically, it is an object to provide a traveling crane having a plurality of member engaging means or the like corresponding to each cover or other member in a row, the crane being of such character that it may be preliminarily conditioned to raise a selected member or members and will thereafter automatically engage, for lifting, only the selected member or members when its member-engaging means or the like is thereafter moved into operative position with respect to the members.

Another object is to provide a crane of the type set forth embodying a plurality of elements movable into and out of positive locking engagement with respective members to be lifted, as distinguished from merely gripping the same in the manner of a pair of tongs, together with a single hoisting means for raising and lowering such elements in unison, and a selector type control for causing them to engage only a selected one or more of the movable members.

Another object is to provide in a crane of the type set forth, and having a plurality of member engaging devices or the like arranged to be lowered and raised simultaneously by a single hoisting means, an improved actuating means for the member engaging devices such that they can not only be preliminarily conditioned to subsequently engage automatically only a selected one or more members when moved into operative relation therewith, but such that they may also be preliminarily conditioned to release a selected one or more of the members which have been

previously raised, such disengagement taking place automatically upon the return of the movable members to lowered position.

Still another object is to provide a crane of the type indicated embodying a plurality of individually operated member engaging devices or the like corresponding to various ones of the movable members to be manipulated, together with a simple and compact arrangement for supporting, as well as simultaneously hoisting and lowering, said devices and their associated actuating mechanisms.

The invention also resides in the novel form of cover engaging device herein disclosed.

Further objects and advantages of the invention will become apparent as the following description proceeds, taken in connection with the accompanying drawings in which:

Fig. 1 is a plan view of a traveling crane embodying the invention, shown as overlying a row of soaking pit covers.

Fig. 2 is a side elevation, partially in section, of the apparatus shown in Fig. 1.

Fig. 3 is a transverse sectional view taken generally along the line 3—3 in Fig. 1.

Fig. 4 is an enlarged perspective view of one of the sub-frame units included in the crane of Fig. 1.

Fig. 5 is an exploded perspective view of one of the cover engaging devices.

Fig. 6 is an end elevation of the device shown in Fig. 5.

Fig. 7 is a wiring diagram of a control circuit used in the crane.

In the exemplary construction the invention has been illustrated as embodied in a traveling crane arranged to manipulate a group of soaking pit covers A, B and C, here shown as three in number and disposed in a single row (Figs. 1 and 2). It will be understood that any reasonable number of covers may be placed in a single row and that further rows, parallel with that shown, may be used if desired. The pit covers A, B and C are of conventional and well known form, each comprising a rectangular frame or shell with a heavy refractory lining on its bottom face. These covers close the throats 10 of corresponding soaking pits which open into a furnace room floor 11. The function of the crane is to manipulate these heavy covers, that is, lift them, traverse them laterally to expose the pit beneath and then return them to their initial positions.

The traveling crane of the present installation comprises a carriage or trolley, designated gen-

erally as 12, arranged to span the row of covers (Figs. 1 and 2). This carriage embodies a pair of longitudinal I-beam side members 13 (see also Fig. 3) rigidly joined by a series of transverse beams 14. To support the carriage 12 for movement in a direction transverse to the row of covers, it is carried on four flanged wheels 15 arranged in pairs at its respective ends and running on rails 16 which extend along the opposite ends of the row of covers and transverse to the row. The wheels 15 are journaled in end frames 17 (see Fig. 3) fixed to the longitudinal I-beams 13.

To traverse the carriage 12 along the rails 16, an electric driving motor 18 (Figs. 1 and 2) is utilized. This motor is connected through a speed reduction gearing 19 with a shaft 20, which extends longitudinally of the carriage 12 and is rotatably journaled in brackets 21 fixed to the forward I-beam 13. At its opposite ends the shaft 20 is connected in driven relation with the adjacent wheels 15 by drive chains 22 (Fig. 3) located in casings 23. Any suitable form of reversing controller (not shown) may be provided for the traversing motor 18.

In order to effect manipulation of the covers A, B and C, through the medium of a single hoisting mechanism on the crane, intermediate connecting devices are provided for establishing an operative connection between the hoisting mechanism and any selected cover or covers. To this end each of the covers is provided with four channels or yokes 24 (Figs. 2 and 3) fixed to its upper side and engageable by a corresponding set of T-heads 25 on the crane. By oscillating a selected set or sets of the T-heads into yoke-engaging position, the corresponding cover or covers are operatively connected to the hoisting mechanism, such covers and only such covers, being lifted by the single hoisting mechanism when the latter subsequently raises all of the sets of T-heads in unison.

As the details of the intermediate connecting mechanism, the yokes 24 (Figs. 5 and 6) are fashioned as heavy channel shaped castings with inturned lips 26. The side walls and lips of the channels are reenforced by suitable integral webs 27. Each of these yokes is rigidly bolted to the metal framework on the top of its corresponding cover. The cooperating T-heads 25 are of generally rectangular form and are integral with the depending ends of vertical rods or rock shafts 28. In a lateral direction the heads 25 are narrower than the gap between the edges of the yoke lips 26 so that when the head is aligned longitudinally with the yoke (as shown in Fig. 5 and in dot-dash lines in Fig. 6) the head can move freely in a vertical direction through the gap in the top of the channel. In a longitudinal direction, however, the heads are longer than the gaps in the tops of the channels so that when swiveled through 90° to the position shown in full lines in Fig. 6, the heads will, upon upward movement of the same, engage the cooperating channels and lift the attached covers. It will be observed that when the crane carriage 12 is being traversed along the rails 16 that the heads 25 can move freely through the channels irrespective of the angular position of the heads. The outer ends of the channel are flared, as shown in Fig. 5, so as to prevent any jamming of the heads as they enter the channels. Not only is a strong and positive lock formed by the T-heads and cooperating yokes but is also a very compact one of minimum overall height. Because no springs or

swinging gripper jaws are required there is little or no liability of breakage of the connecting devices.

To support the T-heads 25 and their actuating mechanisms, separate sub-frames 30 (Fig. 2) are provided, one such sub-frame being used for each set of heads. Each of the sub-frames 30 is identical, one being shown in detail in Fig. 4. It embodies side bars 31, rigidly joined by two pairs of intermediate transverse bars 32 and two pairs of end channels 33. The inner one of each of the end channels 33 is fixed to the ends of the side bars 31 while the outer channels are fixed to the inner channels with spacer blocks 34 between them. In each of these blocks 34 is rotatably journaled (by a suitable heavy duty thrust bearing, not shown) the rock shaft 28 of a corresponding one of the T-heads 25.

Actuation of the T-heads 25 is, in the present instance, accomplished by electric solenoids, a pair of "engaging" solenoids 35^c and a pair of "disengaging" solenoids 36^c being provided for the set of T-heads associated with the cover C (Fig. 4). Similar sets of solenoids 35^a, 36^a, and 35^b, 36^b actuate the T-heads associated respectively with the covers A and B (see Fig. 7). Upon reference to Fig. 4 it will be seen that the armature of each of the T-head "engaging" solenoids 35 is connected with the armature of an opposed 30 "disengaging" solenoid by a rod 37. These rods are in turn tied together by a cross link 38 rigidly connected to them. The outer ends of this cross link 38 are operatively connected to the respective T-head rock shafts 28 through a suitable 35 linkage including longitudinally extending links 39, which are apertured at their centers to receive the inserted ends of the cross link 38 and are pivotally connected to the latter. The outer ends of the links 39 are in turn pivotally connected to rocker arms 40, which are rigid with the respective rock shafts 28.

When the "engaging" solenoids 35^c are energized to draw in their armatures, the rods 37 are pulled axially to the left (as viewed in Fig. 4) 45 thus shifting the links 39 endwise in a corresponding direction and oscillating the rock shafts 28 through 90 degrees. The T-heads 25 are thereby twisted angularly the same distance into position to engage the cooperating channels 24. Similarly, upon deenergization of the solenoids 35^c and energization of the other set 36^c, the linkage is shifted in the opposite direction and the T-heads 25 returned to the position shown. It will be noted that the linkage is not biased 55 in either direction so that merely the deenergization of a previously energized set of solenoids will not shift the linkage.

A single hoisting mechanism is utilized for raising and lowering all three of the sub-frames 30 in unison, as well as any of the covers which may have been engaged by actuation of the corresponding set of T-heads. This hoisting mechanism comprises an electric hoisting motor 41 (Fig. 1) connected through a worm and worm wheel in a casing 42 and a speed reduction gearing indicated at 43 with a shaft 44, which extends longitudinally of the carriage 12 and is rotatably journaled in suitable bearing pedestals fixed to the latter. Fixed on this shaft 44 are three pairs of eccentrics 45, one pair for each of the sub-frames 30. Embracing each of these eccentrics is an eccentric strap 46 (see also Figs. 3 and 4) and depending from each of the straps is an integral arm 47 pivotally connected to an adjacent end of one of the sub-

frames. These pivotal connections include transverse pivot pins 48 passing through registering holes in the arm 47 and brackets 49, fixed to the sub-frame and channels 33 and embracing the lower ends of the arms. A solenoid brake 41a holds the motor 41 against rotation when the motor is idle.

As the hoisting motor 41 rotates the shaft 44 the eccentrics 45 are correspondingly rotated (from the position of Fig. 3 to that of Fig. 4 during hoisting and vice versa during lowering) to raise and lower the sub-frames 30 simultaneously. During such a vertical movement the sub-frames are guided by the projecting upper ends of the rock shafts 28, which are located at their respective four corners, and are received in guide bushings 28a (Fig. 3) fixed on the transverse beams 14 of the carriage 12.

Of particular importance in the present apparatus is the arrangement for effecting the desired selective actuation of the respective sets of T-heads 25. In brief, the arrangement is such that the actuating mechanism may be preliminarily conditioned for moving a selected set or sets of the heads into engaged position while the heads 25 are still displaced from the yokes 24, either in a vertical or horizontal direction, or both. Then, as soon as the heads are moved into operative relation with the yokes 24, i. e. into a position where they are embraced by the latter, the completion of the movement causes the selected heads to be automatically turned into engaged position. Similarly, when a selected one or more of the covers has been elevated by the crane, the mechanism may be preliminarily conditioned for their disengagement, the resulting disengagement being instituted automatically and as soon as the elevated covers have been restored to their initial positions.

By virtue of the provision noted for carrying out what amounts to predetermined cycles of operation in response to preliminary setting of the controls much valuable time is saved in the manipulation of the covers. That such a saving in time is of prime importance will be apparent when it is borne in mind that the number of such comparatively expensive and complicated pieces of apparatus, as the traveling crane shown, which are required for a given number of pit covers, depends directly upon the time consumed in the manipulation of each cover.

The particular control system illustrated (see Fig. 7) is of the electrical type and includes three master switches S^a, S^b and S^c, associated with the cover-engaging devices for the respective covers A, B and C. These switches are of the two-position selector type. Also included in the controls are sets of switches 50 and 51 associated respectively with the "engaging" and "disengaging" solenoids. In each case the pair of "engaging" solenoids 35a and "disengaging" solenoids 36a for each cover are arranged in parallel connected pairs and one of the switches 50 or 51, as the case may be, is connected in series with the pair. Each of these switches includes a movable switch element mounted on the armature of one of the associated solenoids and is arranged to be opened when the armature is fully retracted by energization of the solenoid, and, similarly, to be closed when the armature is pulled in the opposite direction by the opposed solenoid. Finally, the control arrangement includes two limit switches, designated

generally as 52 and 53 (Figs. 1 and 2). The limit switch 52 is actuated by rotation of the hoisting shaft 44 and includes a bridging contact 54 (Fig. 7) which is moved to the closed position shown only when the hoisting shaft is rotated to a position in which the sub-frames 30 are fully lowered. Similarly the other limit switch 53 (Fig. 2) is mounted at the end of the carriage and is actuated from its normally open position to closed position by a stationary cam 53a mounted along the runway in position to actuate the switch when the carriage is properly positioned over the line of pit covers. This switch 53 includes a bridging contact 55 (Fig. 7) which is closed, as shown, only when the crane is positioned over a row of pit covers. Current for the electrical network is furnished from supply lines L₁ and L₂.

In the operation of the traveling crane described, it is traversed along the rails 16 to a position overlying a selected row of pit covers by the traversing motor 18. To condition the apparatus preliminarily to lift a selected cover or covers the corresponding ones of the main switches S^a, S^b, and S^c are shifted to their "engaging" positions (to the right as viewed in Fig. 7). This preliminary selection operation may be performed either while the crane is being traversed to a new row or after it has come to rest over the selected row. The hoisting motor 41 is set in operation to rotate the shaft 44 so that the eccentrics 45 are oscillated from the position of Fig. 4 to that of Fig. 3. In this way all of the sub-frames 30 are lowered simultaneously to a position in which the sets of T-heads 25 enter the corresponding channels 24 (position shown in Fig. 2). The sub-frames can be lowered in this manner either before, after or during the traversing, just as is desired, since the T-heads 25 can enter the ends of the yokes 24 or their tops and hence no interference is offered at this point so long as the T-heads are aligned with the path of crane travel.

As soon as the positioning of the T-heads 25 is completed, as described above, the limit switch sectors 54 and 55 bridge their cooperating contacts (Fig. 7) thereby completing an energizing circuit for the selected "engaging" solenoids. For example, if it is desired to raise the cover A the corresponding master switch S^a will have been previously shifted to its "engaged" or right hand position. Consequently, the subsequent closure of the limit switch contacts 54 and 55, at the completion respectively of the lowering and traversing movements, energizes the solenoids 35a (through a circuit L₁—54—55—56—50—35a—S^a—L₂). Energization of these solenoids 35a causes them to retract their armatures thus oscillating the rock shafts 28 for the T-heads 25 associated with the cover A, through the medium of the linkage previously described, into a position in which these T-heads engage the cooperating yokes 24 on the cover A. As soon as the armatures of solenoids 35a reach their fully retracted position the corresponding switch 50 is opened, thereby again deenergizing these solenoids so that they will not become overheated during long continued energization.

Having engaged the selected cover A in the manner described, the hoisting motor 41 is set in operation to raise all of the sub-frames 30 simultaneously. These rising sub-frames will bring with them only the engaged cover A, however, since the other sets of T-heads 25, which have

not been rotated from their disengaged positions, can move freely away from the associated yokes 24. After the cover A has been elevated the carriage 12 is traversed along the rails 16 so that the cover clears the top of its pit for the insertion or removal of a billet or ingot. Thereafter, the cover can be restored to its initial position over the pit throat 10 and other pit covers removed and replaced as desired.

In restoring the cover A to its initial position its main switch S^a is thrown to the "disengaged" or left hand position (Fig. 7) as a preliminary operation while the cover A is still displaced from its pit. It will be observed that this does not cause the crane to drop the cover immediately since the limit switch contact 54 is open so long as the hoisting mechanism is not in its lowered position and contact 55 is open so long as the crane is laterally displaced from the row of pits, and hence, a circuit is not completed for the disengaging solenoids 36^a merely by shifting the switch S^a. After the carriage 12 has been traversed back to a position overlying the row of covers, however, and the cover A lowered to its pit closing position, the limit switch contacts 54 and 55 reclose. Thereupon the T-heads 25 are automatically disengaged from the cover A since the solenoids 36^a are energized (through a circuit L₁—54—55—56—51—36^a—S^a—L₂). Energization of these solenoids 36^a oscillates the rock shafts 28, of the T-heads 25 associated with the cover A, back to their initial or disengaged position. Completion of the retracting movement of the armatures for the solenoids 36^a opens the associated switch 51 thereby deenergizing them and restoring the circuit to the condition shown in Fig. 7 preparatory to the performance of subsequent selection cycles.

The function of the switch contacts 54 and 55 in instituting preselected movements of the T-heads, or in other words, their function in a positive sense will be clear from the description above. It should also be observed that, in a negative sense, they further act as interlocks to prevent oscillation of the T-heads except when the latter are in predetermined position with respect to the pits and covers.

From the foregoing it will be seen that a traveling crane has been provided which is capable of great versatility of operation in manipulating selected ones of a series of pit covers since the T-heads 25 operatively engage the yokes 24 only when the T-heads are rotated to an engaged position, and irrespective of whether or not the T-heads are in raised or lowered position, the crane can be traversed back and forth over the rows of pits with great freedom. Also, particularly characteristic of the crane herein disclosed is the speed of operation which may be achieved due to the provision of means for preselection of the covers which are to be engaged or disengaged and automatic institution of the selected operation as soon as the parts are properly positioned for it to take place. Complete safety of operation is insured by the arrangement set forth. The control switches can, of course, be mounted for manipulation from a suitable station on the hoist or at some remote point, as may be desired in any particular installation, the use of electric controls making such location possible.

I claim as my invention:

1. The combination of a crane arranged to span longitudinally a row of movable members such as soaking pit covers, a plurality of devices

on said crane shiftable into and out of engagement with respective ones of said members when positioned in operative relation with them, means on said crane for simultaneously raising and lowering all of said devices and any member or members engaged by the latter, actuating means for moving individual ones of said devices into and out of member-engaging position, a pre-selection control means associated with said actuating means for preliminarily conditioning the latter to move a selected one or more of said devices into member-engaging position, and means actuated automatically in response to a completion of the movement of said devices into operative relation with the members for instituting the operation of said actuating means with respect to the preselected one or ones of said member-engaging devices.

2. The combination of a crane arranged to span longitudinally a row of movable members such as soaking pit covers, a plurality of devices on said crane shiftable into and out of engagement with respective ones of said members when positioned in operative relation with them, means on said crane for simultaneously raising and lowering all of said devices and any member or members engaged by the latter, actuating means for moving individual ones of said devices into and out of member-engaging position, a pre-selection control means associated with said actuating means for not only conditioning the latter to move a preselected one of said devices into member-engaging position but for also conditioning said actuating means to move other selected one or ones of said devices to member-disengaging position, and means actuated automatically in response to a completion of the movement of said devices into operative relation with the members for instituting the operation of said actuating means, to move various ones of said devices to member-engaging and member-disengaging position in accordance with the pre-selection setting of said control means.

3. The combination of a crane arranged to span longitudinally a row of movable members such as soaking pit covers, a plurality of devices on said crane shiftable into and out of engagement with respective ones of said members when positioned in operative relation with them, means on said crane for simultaneously raising and lowering all of said devices and any member or members engaged by the latter, actuating means for moving individual ones of said devices into and out of member-engaging position, pre-selection control means associated with said actuating means for preliminarily conditioning the latter to move a selected one or more of said devices out of member-engaging position, and means actuated automatically in response to the completion of the repositioning of the members in respective predetermined positions therefor for instituting the operation of said actuating means to move the preselected device or devices to member-disengaging position.

4. The combination of a hoist mechanism movable between raised and lowered positions, intermediate means between the hoisting means and a plurality of movable members such as soaking pit covers for rendering said hoisting mechanism operable to raise and lower any selected one or more of said members, and pre-selection control means for said intermediate means operable at will to condition the same preliminarily to render the hoisting mechanism operative to lift a selected one or more of said

members, said control means being automatically operable after such preliminary conditioning to effect a completion of the operation of said intermediate means in response to completion of a predetermined positioning of said intermediate means with relation to predetermined rest positions for said members.

5. The combination of a hoist mechanism movable between raised and lowered positions, intermediate means between the hoisting means and a plurality of movable members such as soaking pit covers for rendering said hoisting mechanism operable to raise and lower any selected one or more of said members, and preselection control means for said intermediate means operable at will to condition the same preliminarily to render the hoisting mechanism operative to lift or to release selected ones of said members, said control means being automatically operable after such preliminary conditioning to effect a completion of the operation of said intermediate means in response to completion of a predetermined positioning of said intermediate means with relation to predetermined rest positions for said members.

6. The combination of a crane arranged to span longitudinally a row of movable members such as soaking pit covers; a row of abutments carried by the crane and adapted to engage with mating abutments in respective ones of the movable members, the pairs of complementary abutments on the crane and members respectively being movable individually relative to each other into and out of engagement when positioned in operative relation; a single hoisting means on the crane for raising and lowering in unison all of the abutments carried by the crane; actuating means for effecting relative movement between selected pairs of said complementary abutments to shift them into or out of engagement; and interlock means for preventing operation of said actuating means except when the abutments carried by the crane are in lowered position.

7. The combination with a group of soaking pit covers aligned in a row, of a crane arranged to span the row longitudinally and to move laterally of it; an abutment on each of said covers and a mating abutment, for each of those on the covers, carried by the crane, the pairs of complementary abutments being movable individually relative to each other into and out of engagement when positioned in operative relation; a single hoisting means on the crane for raising and lowering in unison all of the abutments carried by the crane; actuating means for effecting relative movement between selected pairs of said complementary abutments to shift them into or out of engagement; and interlock means for preventing operation of said actuating means except when the crane is located in predetermined position over the row of covers.

8. The combination of a hoisting mechanism movable between the raised and lowered positions, individual means for releasably connecting each of a plurality of movable articles to be hoisted to the hoisting mechanism, said last named means including pairs of mating mechanically engageable members carried respectively by the hoisting mechanism and respective ones of the movable articles, said members being movable relative to each other into and out of positive locking engagement when the hoisting mechanism is in lowered position, individually operable actuating means for each of said pairs

of members and including alternatively energizable electric circuits, each of said actuating means being operable to engage and disengage the associated pair of members upon completion of a corresponding one of said circuits, a manually operable master switching device for each of said actuating means for alternatively closing a pair of contacts in one of said circuits for its actuating means and opening a pair of contacts in the other and vice versa, and a limit switch having contacts interposed in all of said circuits and which are closed only when said hoisting means is in its lowered position.

5. The combination of a hoisting mechanism movable between raised and lowered positions, intermediate means between the hoisting means and a plurality of movable members such as soaking pit covers for rendering said hoisting mechanism operable to raise and lower any selected one or more of said members, and preselection control means for said intermediate means operable at will to condition the same preliminarily to render the hoisting mechanism operative to lift or to release selected ones of said members, said control means being automatically operable after such preliminary conditioning to effect a completion of the operation of said intermediate means in response to completion of a predetermined positioning of said intermediate means with relation to predetermined rest positions for said members.

15. The combination with a plurality of soaking pit covers, of a hoisting mechanism movable between raised and lowered positions, means including mating abutments carried by the hoisting mechanism and covers respectively and engageable in positive locking relation for releasably connecting individual ones of said covers to the hoisting mechanism, said abutments carried by the hoisting mechanism being raised and lowered in unison by it, and means for selectively actuating individual ones of the mating abutments into and out of engaged position.

20. A traveling crane comprising, in combination, a wheel-supported carriage frame, a plurality of sub-frames movably mounted on said carriage frame, a hoisting mechanism on said carriage frame for hoisting and lowering said sub-frames in unison, mechanical connecting devices on each of said sub-frames movable into and out of load-engaging position, actuators on each of said sub-frames for moving corresponding 35 ones of said connecting devices, and a unified control system for selectively operating said actuating means.

25. The combination of a traveling crane comprising, in combination, a wheel-supported carriage frame, a plurality of sub-frames movably mounted on said carriage frame, a hoisting mechanism on said carriage frame for hoisting and lowering said sub-frames in unison, mechanical connecting devices on each of said sub-frames movable into and out of load-engaging position, actuators on each of said sub-frames for moving corresponding ones of said connecting devices, a unified control system for selectively operating said actuating means, and interlock means for preventing operation of said actuators except when all of said sub-frames are in their lowered positions.

30. A traveling crane for manipulating selected ones of a row of soaking pit covers comprising, in combination, a wheel-supported carriage frame, a plurality of sub-frames movably mounted on said carriage frame a hoisting mechanism on said carriage frame for hoisting and lowering said sub-frames in unison, a set of load-engaging devices rotatably mounted on each of said sub-frames and each of said devices having an operating rock shaft operable upon oscillation thereof to move the corresponding devices into and out of positive locking engagement with complementary abutments on respective ones of the covers, a mechanical linkage on each sub-frame interconnecting the several rock shafts thereon, an actuator on each of said sub-frames for operating the linkage thereon, and a unified control system for selectively operating said actuators.

35. In a traveling crane for manipulating a group of soaking pit covers, the combination of a wheel-supported carriage frame, a plurality of sub-frames, a vertically extending rock shaft journaled in each of said sub-frames and pro-

jecting through guide means on said carriage frame and guiding the sub-frames for vertical movement with respect to said carriage frame, hoisting means on said carriage frame for hoisting and lowering said sub-frames in unison, laterally projecting upwardly facing abutments rigid with the lower ends of said rock shafts and engageable in positive locking relation with complementary downwardly facing rigid abutments on corresponding ones of the pit covers, and actuators carried by said sub-frames for oscillating said rock shafts.

14. In a traveling crane for manipulating a group of soaking pit covers, the combination of a wheel-supported carriage, a plurality of vertically extending rock shafts having T-heads on their lower ends engageable with complementary abutments on the covers in predetermined angular positions of the T-heads, means for selectively oscillating said rock shafts, and hoisting means on the carriage for raising and lowering said rock shafts in unison.

15. In an installation of the type set forth the

combination of a traveling crane arranged to span longitudinally a row of individually movable members to be manipulated, a plurality of rock shafts depending from the crane above respective ones of the movable members and having T-heads thereon, complementary upwardly facing yokes adapted to be fixed on the respective ones of the movable members, said yokes being shaped to permit the T-heads to pass freely therethrough vertically when the T-heads are aligned with the path of crane travel and to engage the T-heads when the latter are turned to a position transverse to the path of crane travel, and said yokes also being shaped to permit the T-heads to pass freely therethrough in a horizontal direction paralleling the path of crane movement irrespective of the angular adjustment of the T-heads, means for selectively actuating said rock shafts to turn selected ones of said T-heads into and out of their yoke-engaging positions, and hoisting means for raising and lowering the rock shafts in unison.

JOHN E. MINTY.
